DES. 2096

Letters Patent No. 2096 Dated June 18-1865.

Design for a Bust of Abraham Lincoln.

The schedule referred to in these Letters Patent and making part of the same.

To all whom it may concern:

Be it known that W. H. Philip of Brooklyn, in the County of Kings and State of New York, have invented or produced a new and Original Bust of Abraham Lincoln, late President of the United States of America; and I do hereby declare that the same is fully and clearly illustrated in the one mixed photographic views forming a part of this specification.

Every person, and especially every patriotic citizen, desires to possess a correct representation as possible of such men as have rendered themselves famous and dear to their countrymen by statesmanship, heroic deeds and many other qualities with which they were endowed and which they exercised during their lifetime.

The subject of the present application for a patent is a bust of Abraham Lincoln our late lamented President, and it is represented by three photographic views as follows:

Figure 1 is a nearly front view of the bust.

Figure 2 is a three quarter view of the left side thereof.

Figure 3 is a profile view of the right side.

The model or model from which the cast of this bust was taken I made in July 1864, under Mr. Lincoln's immediate supervision, he having offered me a dozen sittings or so as was deemed necessary to complete it and I went to the visit him down after day and fashioned my clay model until it was completed. Mr. Lincoln appeared to take considerable interest in the work and examined each day's progress with care, and when the model was finished he said "I consider that a very good bust, and a very good likeness."

DES. 2096

2

I have obtained the first which I can protect
by Letters Patent and I will hereon make that it is the last bust which
was moulded from Mr. Lincoln's living features, and the same is
to be the most correct in existence.

The bust is so correctly delineated in the Photo-
graphic views that a particular description thereof would be
superfluous.

I am an original with one, and desire to secure
by Letters Patent.

The bust of Abraham Lincoln as represented in the
photographic views thereto hereunto annexed.

Witnesses:

M. H. Livingston
J. G. W. Albert H. Brown.
